(57) **CLAIM**

The ornamental design for a whiskey bullet, as shown and described.

DESCRIPTION

FIG. 1 is a front perspective view of a whiskey bullet, showing our new design;

FIG. 2 is a first side elevation view thereof;

FIG. 3 is a second side elevation view thereof;

FIG. 4 is a front elevation view thereof;

FIG. 5 is a back elevation view thereof; and,

FIG. 6 is a top plan view thereof.

Any broken lines in the Figures do not form a part of the claimed design.

1 Claim, 6 Drawing Sheets
